UNITED STATES PATENT OFFICE.

CHARLES H. MOORE, OF YONKERS, NEW YORK.

WATER-CLOSET.

SPECIFICATION forming part of Letters Patent No. 624,959, dated May 16, 1899.

Application filed January 9, 1894. Serial No. 496,271. (No model.)

To all whom it may concern:

Be it known that I, CHARLES H. MOORE, a citizen of the United States, residing at Yonkers, in the county of Westchester and State 5 of New York, have invented a new and useful Water-Closet, of which the following is a specification.

The object of my invention is to provide an earthenware water-closet having a box or 10 chamber at the back of the bowl, integral with it and independent of the water-supply inlet, to secure seat-hinges to in a manner to allow the seat to be swung clear of the bowl, so as to admit of the entire surface of the 15 bowl being cleaned and to prevent any strain on the earthenware.

In the accompanying drawings, forming a part of this specification, Figure 1 is a vertical view, partly in section, of a portion of 20 a closet-bowl provided with a box or chamber to which hinge-fittings are attached. Fig. 2 is a side view showing extension fittings or plates secured to the vertical sides of the box. Fig. 3 is a view showing the extension 25 fittings or plates secured to the vertical sides of the box.

Heretofore in earthenware water-closets having projecting pieces at the back of the bowl to secure seat-hinges to they have usually 30 been in the shape of lugs or a shelf. In my invention I use a box or chamber joined to the back of the bowl at the center, but made independent of the water-supply chamber, inasmuch that although it is made integral 35 with the bowl and water-supply inlet or chamber it is separated from it by an earthen wall, so that water does not enter it, but, being joined to the water-supply chamber, it adds strength to it and makes a support for the 40 seat that is not liable to warp in the process of baking and is in no way liable to break from usage. This box or chamber is less in length than the width of the bowl and may be put on any closet having a round or straight 45 back.

1 shows an earthenware water-closet having a water-inlet chamber 2.

3 is an earthen projection at the back of the bowl to form a top or shelf for the box or 50 chamber 5.

4 represents projecting pieces that form the vertical sides of the box. These sides 4 can

be any desired depth so long as there is sufficient room for the bolts 7.

6 represents apertures made in the vertical 55 sides of the projecting pieces.

7 shows bolts secured in the apertures 6.

8 represents flanged rubber rings surrounding the bolts 7 to keep the metal bolts from coming in contact with the earthenware. 60

9 represents rubber rings on the bolts 7 and within the hinges to prevent jarring the earthenware by any movement of the seat.

10 shows extension fittings or plates which I use when it is desirable to get the axis of 65 the hinges higher than the apertures with the bolts 7 only fastened in them will permit of.

11 represents nuts that hold the extension-fittings in place.

12 shows pintles on the extension-fittings 70 for the hinges to operate on.

13 shows the hinges.

14 represents pieces projecting in on the earthenware from the extension-fittings to prevent the upper end of the said extension- 75 fittings from shifting.

15 shows the seat to which the hinges are secured.

The advantages are, first, by the use of a box or a shelf and vertical sides 4 a greater 80 supporting-surface to the wall of the closet is obtained than if lugs or a strip only are used; second, when the seat is raised the entire top surface of the bowl can be cleaned; third, simple and effective way to operate the seat. 85

Having described my invention, what I claim as new, and desire to secure by Letters Patent, is—

1. The combination with an earthenware water-closet having a seat secured directly to 90 the bowl, of an earthen projection extending out from and across the center of the back portion of the closet-bowl and of less length than the width of the said bowl, and having apertures made in the vertical sides, hinge-fittings secured in the apertures, a seat secured to the hinges and the water-supply 95 chamber separated from the apertures by an earthen wall.

2. The combination with an earthenware 100 water-closet, of a box or chamber made integral with the bowl and extending in a horizontal direction from one side of the water-supply inlet to the other expressly for the

purpose of supporting hinge-fittings, the said chamber being separated from the water-supply inlet by an earthen wall and having apertures in the vertical sides, hinge-fittings secured to the said apertures, and a seat secured to the hinges.

3. The combination with an earthenware water-closet, of a box or chamber 5 projecting out from the rear of the bowl, hinge-fittings secured to the vertical sides of the said box or chamber, the water-inlet chamber 2 within the box or chamber 5, and a seat secured to the hinge-fittings.

4. The combination with an earthenware water-closet having a projection or box extending across the center of the back portion of the bowl, and of less length than the width of the bowl and having apertures in the vertical sides, of extension fittings or plates se-

cured to the vertical sides and having pieces 20 14 project in on the earthenware in a manner to prevent the upper ends of the said extension fittings or plates from moving, hinges secured to the extension fittings or plates and a seat secured to the hinges.

5. The combination with an earthenware water-closet, of two distinct chambers made at the rear of the bowl, the chamber 2 being for the purpose of introducing water to the bowl, and the chamber 5 having apertures in 30 the vertical sides, hinge-fittings secured to the apertures and a seat secured to the hinges, as and for the purpose set forth.

C. H. MOORE.
